UNITED STATES PATENT OFFICE.

FRANK AUBIN, OF NEW YORK, N. Y.

SASH-FASTENER.

1,232,170.

Specification of Letters Patent.

Patented July 3, 1917.

Application filed June 15, 1915. Serial No. 34,246.

To all whom it may concern:

Be it known that I, FRANK AUBIN, a citizen of the United States, residing at New York, in the county of New York and State 5 of New York, have invented certain new and useful Improvements in Sash-Fasteners, of which the following is a specification.

My invention relates to sash fasteners, and more particularly to that class of sash fasteners employing a locking link and a sliding 10 bolt.

The primary object of my invention is to provide a sash fastener of the above class which will positively and securely lock the 15 sashes of a window in closed position, and which will prevent rattling of the sashes.

Another object of my invention is to provide a sash fastener of the class above described which is simple in construction, 20 cheap to manufacture, strong and durable, and effective in operation.

With the above and other objects in view my invention resides preferably in the construction, combination, and arrangement of 25 parts as hereinafter set forth, in the specification and illustrated in the accompanying drawings, in which—

Figure 1 is a top plan view of a portion of the meeting rails of an upper and lower 30 sash showing my improved sash fastener in position and locked.

Fig. 2 is a side elevation of the same.

Fig. 3 is a transverse sectional view taken on the line 3—3 of Fig. 1.

Similar reference characters indicate similar parts throughout the various views of the drawings.

In the drawings wherein the preferred embodiment of my invention is illustrated, 40 I have designated the upper and lower sashes of any ordinary type 1 and 2, respectively.

My invention comprises two component 45 parts, namely, a retaining link and a locking sliding bolt. I provide a casing 3 mounted on the upper face of the meeting rail 2, said casing serving to house a slideable bolt 4 having a handle 5 extending laterally therefrom. It will be apparent 50 that a longitudinally disposed centrally located aperture 6 is provided in the casing 3 in which the bolt 4 is adapted to be reciprocated. The casing 3 is provided with an elongated aperture 7 communicating with 55 the central aperture 6 and is provided with a right angular portion 8 for reception of

the handle 5 when in locked position, as shown to advantage in Figs. 1 and 2. The base portion of the casing 3 is extended to provide ears 9 through which fastening 60 screws 10 pass for retaining the casing in position on the meeting rail 2.

An upstanding portion or lug 11 is mounted on the extended base portion of the casing 3 and is provided with an aperture 12 disposed therein concentrically with the aperture 6. The aperture 12 is adapted to receive one extremity of the sliding bolt when in locked position, as shown to advantage in Figs. 1 and 2. A plate or base 13 70 is mounted upon and screwed to the meeting rail 1 by means of screws or the like 14. A plurality of lugs 15 are provided on the plate 13 and project upwardly therefrom and serve as bearings for a pin 16, said pin 75 16 having a connecting or retaining link 17 hingedly mounted thereon. The link 17 is preferably tapered slightly throughout its length to facilitate its insertion between the lug 11 on the base portion of the casing 3 80 and one extremity of said casing. The free extremity of the link 17 is enlarged as at 18 and provided with a laterally extending aperture 19, said aperture being adapted to register with the apertures 12 and 6 to receive the sliding bolt 4, as shown to advantage in Fig. 3.

It will be noted that when locking the upper and lower sashes, the link 17 is moved into the position shown to advantage in Fig. 90 3 and the bolt 4 slid into engagement therewith. This will not only lock the window against opening by unauthorized persons, but will effectively prevent rattling of the 95 sashes. It is to be understood, of course, that various changes may be made in the minor details of the device which do not depart from the spirit and scope of the same as claimed.

What is claimed is:

1. A lock for window sashes, including a casing adapted to be secured to the upper face of the meeting rail of the lower sash, a sliding bolt in said casing, a lug in line with said casing and spaced from the same, 105 said lug being formed integrally with the casing, a base plate secured to the lower meeting rail of the upper sash, bearing portions on said base plate at one edge thereof adjacent to the first mentioned meeting rail, 110 a tapered link carried by said bearing portions, a laterally enlarged circular portion

100

on said link at the reduced end thereof and having a laterally extending axial aperture adapted to align with the casing and lug, said link being adapted for reception between said casing and said lug at its narrow end to receive said sliding bolt, and means to positively hold said sliding bolt against movement in the last named position.

2. A sash fastener comprising an elongated casing with a base plate having end lugs for attachment thereof to the top rail of the lower sash of a window, said casing having a longitudinally disposed centrally located aperture therethrough and a communicating elongated slot in its wall provided with a right angular portion at one end, a lug integral with the base plate, spaced from the casing and having an aperture alining with the aperture of the casing, a bolt slidable in the casing and having a handle projecting through the slot for shifting the bolt in the aperture to project the

same through the space and into the lug, a base plate adapted for attachment to the top face of the lower rail of the upper sash of the window and having a pair of spaced apertured lugs at its edge adjacent the other rail, and a retaining link pivoted in the lugs of the base plate and tapered toward its free end, said free end having an enlarged transversely apertured portion adapted when the link is swung in the arc of half a circle between the casing and first mentioned lug, to receive the bolt therethrough, said bolt being designed to be manually shifted and turned when moved to engaged or disengaged positions.

In testimony whereof I affix my signature in presence of two witnesses.

FRANK AUBIN.
